DEASHING RESIDUAL OILS WITH AN ACID OF PHOSPHORUS

Filed Dec. 7, 1951

UNITED STATES PATENT OFFICE

2,682,496

DEASHING RESIDUAL OILS WITH AN ACID
OF PHOSPHORUS

Roger W. Richardson, Baton Rouge, La., and Cecil H. Hale, Austin, Tex., assignors to Standard Oil Development Company, a corporation of Delaware

Application December 7, 1951, Serial No. 260,392

5 Claims. (Cl. 196—50)

1

The present invention is concerned with an improved process for the removal of ash forming constituents from petroleum oils, particularly from petroleum oils remaining after distillation of volatile components. The invention is more particularly concerned with an improved process for the preparation of high quality motor fuels, heating oils and for the preparation of satisfactory feed stocks for a fluid catalytic cracking operation. In accordance with the present invention, undesirable high ash forming constituents are removed from petroleum oils, particularly from high boiling petroleum oils by an operation which comprises treating these oils with a phosphorous compound followed by the removal of the reaction constituents, preferably with an aqueous solvent.

It is well known in the art to treat mineral oils by various processes in order to remove undesirable constituents from these oils. For example, it is known to employ light hydrocarbon solvents, as for example, hydrocarbons such as propane and butane in order to remove undesirable constituents, as for example, asphaltic constituents therefrom. In these operations various temperatures and pressures are employed, as well as various solvent to oil ratios. It is also known in the art to use various processes for the removal of gum and ash-forming constituents therefrom. Other processes have been directed toward the preparation of satisfactory high boiling feed stocks for fluid catalytic cracking operations.

For example, it is known in the art that crudes contain ash materials which normally comprise compounds of metals such as salts of sodium, silicon, iron, calcium, magnesium, nickel and vanadium. These ash constituents are either oil soluble or are so finely dispersed that they can be settled or filtered out only with great difficulty. When the crudes are fractionated, these compounds tend to be concentrated in the heavier fractions which may be employed as cracking feed stocks. This is particularly true of the residuum or "bottoms" fractions which contain high quantities of ash which it has not heretofore been possible to satisfactorily remove. When the feed stocks contain significant amounts of these metallic compounds, they tend to accumulate on the catalysts and act as poisons necessitating the removal and replacement of the catalyst at much more frequent intervals than is normally the case when using clean feed stocks. As a matter of fact, the catalyst tends to become contaminated or "poisoned" so quickly when processing residual stocks that replacement costs become

2

prohibitive. For these reasons, such residual stocks are not normally fed to fluid catalytic cracking units.

It has now been discovered that undesirable high ash forming constituents may be more efficiently removed from feed stocks boiling in their reduced crude boiling range, providing the oil is heated and treated with a phosphorous compound followed by the removal of undesirable constituents with a solvent, as for example, with an aqueous solvent. The process of the present invention may be readily understood by reference to the drawing illustrating one embodiment of the same.

15 Referring specifically to the drawing, a feed oil, as for example, a West Texas crude, is introduced into distillation zone 1 by means of feed line 2. Temperature and pressure conditions are adjusted in zone 1 to secure the desired fractionation of the crude oil. Low boiling hydrocarbon gases are removed overhead by means of line 3; a lower boiling hydrocarbon fraction is removed by means of line 4, a higher boiling hydrocarbon fraction is removed by means of line 5, and a somewhat higher boiling fraction is removed by means of line 6. A fraction boiling in the reduced crude boiling range, as for example, in the range above about 600° to 700° F., preferably boiling in the range above 850° F., is segregated as a bottoms fraction by means of line 7. It is to be understood that zone 1 may comprise any suitable number and arrangement of distillation zones or stages.

20 In accordance with the present invention, the high boiling oil if cooled is raised to an elevated temperature in a heating zone. However, it is preferred to add the compound of phosphorus directly to the hot oil as it is withdrawn from zone 1. Thus the compound of phosphorus, as for example an 85% phosphoric acid is added from line 50 by means of line 51. The mixture is then passed to treating or soaking zone 9 by means of line 10 wherein the oil and acid are thoroughly mixed by means of mixer 11. Any evolved gases are removed from zone 9 by means of line 12. It is to be understood that treating zone 9 likewise may comprise any suitable number and arrangement of stages.

25 The treated oil is withdrawn from zone 9 by means of line 13 and introduced into a solvent washing zone 14. The oil is contacted in zone 14 with a suitable solvent, preferably with water, which is introduced by means of line 15 as steam. Temperature and pressure conditions in zone 14 are adjusted to secure the desired removal of the

undesirable material from the oil. Water is recycled from the bottom of zone 14 to the top by means of line 16, pump 17, line 18, and spray means 19. Additional water may be added by means of line 20. Washing zone 14 may comprise any suitable number and arrangement of stages.

The treated and washed oil is removed from zone 14 by means of line 21 and passed into a solvent separation zone 22. The water containing the acid and ash forming materials is removed by means of line 23 while the treated oil free of water and undesirable constituents is removed by means of line 24. This oil may be removed from the system by means of line 25 and used as a heating oil or as a feed stock for various other processes which require that the oil be free or substantially free of high ash forming constituents.

However, a preferred adaptation of the invention is to combine the foregoing with a fluid catalytic cracking operation. As pointed out heretofore, the use of reduced crudes in a catalytic cracking operation has presented problems due to the fact that it has not been possible heretofore to remove ash forming constituents from these high boiling reduced crudes to a satisfactory extent. The presence of these constituents in a feed oil in a fluid catalytic cracking operation causes excessive formation of carbon on the catalyst, thus substantially decreasing the activity of the catalyst. Therefore, in accordance with a preferred adaptation of the present invention, the treated oil free of undesirable iron, vanadium and nickel and other compounds is removed from zone 22 by means of line 24 and introduced into a fluid catalytic cracking operation. The fluid catalytic cracking plant is composed of three sections: cracking, regeneration and fractionation. The cracking reaction takes place continuously in one reactor, the spent catalyst being removed continuously for regeneration in a separate vessel, from which it is returned to the cracking vessel. Continuity of flow of catalyst as well as of oil is thus accomplished, and the characteristic features of fixed-bed designs involving the intermittent shifting of reactors through cracking, purging, and regeneration cycles are eliminated.

Regenerated catalyst is withdrawn from the regenerator and flows by gravity down a stand-pipe, wherein a sufficiently high pressure head is built up on the catalyst to allow its injection into the fresh liquid oil stream. The resulting mixture of oil and catalyst flows into the reaction vessel, in which gas velocity is intentionally low, so that a high concentration of catalyst will result. The cracking that takes place results in carbon deposition on the catalyst, requiring regeneration of the catalyst. The cracked product oil vapors are withdrawn from the top of the reactor after passing through cyclone separators to free them of any entrained catalyst particles, while the spent catalyst is withdrawn from the bottom of the reactor and is injected into a stream of undiluted air which carries the catalyst into the regeneration vessel. The products of combustion resulting from the regeneration of the catalyst leave the top of this vessel and pass through a series of cyclones where the bulk of the entrained catalyst is recovered. The regenerated catalyst is withdrawn from the bottom of the vessel to complete its cycle.

Again referring specifically to the drawing, in accordance with a preferred adaptation of the present invention, the treated oil removed by

means of line 24 is introduced into a catalytic cracking zone 25.

Temperature and pressure conditions in cracking zone 25 are adjusted to secure the desired conversion of the feed oil. Cracked products are removed overhead from zone 25 by means of line 26 and passed into a fractionation zone 27. Temperature and pressure conditions in fractionation zone 27 are adjusted to remove overhead by means of line 28 hydrocarbon constituents boiling in the gasoline and lower boiling ranges. This stream is passed to a stabilizing unit where a gasoline fraction of the desired volatility is segregated. A heating oil fraction is removed by means of line 29 while a fraction boiling in the cycle oil boiling range is removed by means of line 30. A bottoms fraction is removed by means of line 31 and handled as desired. Spent catalyst is removed from the bottom of zone 25 by means of line 32 and passed into a regeneration zone 33 by means of line 34. Sufficient air is introduced into the system by means of line 35. Regenerated catalyst is removed from the bottom of zone 33 by means of line 36 and passed to the reactor along with the feed by means of line 24.

Since the viscosity of the residual oil is relatively high, a preferred mode of operation is to add a lower boiling oil, as for example, a gas oil, to the residual oil by means of line 32 as the residual oil passes into the water washing zone 14. Under certain conditions it may also be desirable to add a lower boiling oil to the residual oil in line 24 by means of line 33.

The invention is broadly concerned with the removal of ash forming constituents from high boiling residual oils. The invention is specifically concerned with an improved process for the production of motor fuels utilizing a fluid catalytic cracking operation, wherein the feed to the catalytic operation comprises a residual oil. In accordance with the present invention the ash forming constituents in residual oils are removed by heating the residual oils to elevated temperatures, below which cracking occurs, in the presence of a small amount of a compound of phosphorus followed by the removal of undesirable constituents utilizing a solvent. It is preferred that the compound of phosphorus comprise an acid of phosphorus. However, oxides of phosphorus may also be utilized.

When utilizing an acid of phosphorus the concentration of the acid should be in the range from about 60% to 100%. A preferred concentration is in the range from about 80% to 90%. The quantity of acid employed may be in the range from .05% to 10% by volume based upon the feed. A preferred amount employed is in the range from about 1% to 3% by volume.

The preferred feeds for use in conjunction with the present invention are residual oils wherein the gravities are below about 15° API, preferably below about 12° API. These oils should boil preferably above about 600° to 700° F.

Treating temperatures for contacting the compound of phosphorus and the oil are in the range of about 500° F. to 800° F. Preferred treating temperatures are in the range from about 600° F. to 700° F. The time of contact likewise may vary appreciably, as for example, from about 15 minutes to 6 hours. Preferred times of contact are in the range from about 2 to 3 hours.

In addition to or in place of water washing, the treated oil may be centrifuged, percolated through slightly alkaline material, or filtered,

or a combination of these treatments may be used. Regardless of the method used, it is important that the ash constituents which have been agglomerated and/or made water soluble by the heat treatment with phosphoric acid be removed. Water washing is generally sufficient, but any one or a combination of the other methods may be used instead or in conjunction with the water washing. Under some conditions, it may be desirable to form an emulsion and then break it, and subsequently remove the water containing the soluble catalyst poisons.

Thus by the present invention, residual stocks which would otherwise have to be sold as low cost, heavy fuel oil or otherwise used as low grade, heavy products are converted to valuable catalytic cracking feed which may be cracked over catalysts, without undue contamination, to yield high octane gasoline and other valuable products normal to the fluid catalytic cracking operation.

As discussed above, the invention is particularly concerned with an improved operation which comprises the treatment of a reduced crude by contacting it with a compound of phosphorus, removing a residue and utilizing the treated stock to secure an improved catalytic cracking operation. It is well known in the art to produce cracked naphthas by a fluidized solids catalytic operation wherein the cracked product comprises constituents boiling in the motor fuel boiling range, as for example, below about 430° F. The cracked product also comprises normally gaseous constituents, as for example, those containing three carbon atoms and less in the molecule. The fluidized solids technique for processing feed fractions, as for example, gas oils, heavy residuums and other feed stocks for the production of hydrocarbon fractions boiling in the motor fuel boiling range is a conventional one. As discussed heretofore, the system of a fluidized solids technique comprises a reaction zone and a regeneration zone, employed in conjunction with a fractionation zone. The reactor and the catalyst regenerator are arranged at approximately an even level. The operation of the reaction zone and the regeneration zone is conventional, which preferably is as follows:

An overflow pan is provided in the regeneration zone at the desired catalyst level. The catalyst overflows into a withdrawal line which preferably has the form of a U-shaped seal leg connecting the regeneration zone with the reaction zone. The feed stream introduced is usually preheated to a temperature in the range from about 500° to 650° F. in exchangers in heat exchange with regenerator flue gases which are removed overhead from the regeneration zone, or with cracked products. The heated feed stream is withdrawn from the exchangers and introduced into the reactor. The seal leg is usually sufficiently below the point of feed oil injection to prevent oil vapors from backing into the regenerator in case of normal surges. Since there is no restriction in the overflow line from the regenerator, satisfactory catalyst flow will occur as long as the catalyst level in the reactor is slightly below the catalyst level in the regenerator when vessels are carried at about the same pressure. Spent catalyst from the reactor flows through a second U-shaped seal leg from the bottom of the reactor into the bottom of the regenerator. The rate of catalyst flow is controlled by injecting some of the air into catalyst transfer line to the regenerator.

The pressure in the regenerator may be controlled at the desired level by a throttle valve in the overhead line from the regenerator. Thus, the pressure in the regenerator may be controlled at any desired level by a throttle valve which may be operated, if desired, by a differential pressure controller. If the pressure differential between the two vessels is maintained at a minimum, the seal legs will prevent gases from passing from one vessel into the other in the event that the catalyst flow in the legs should cease.

5 The reactor and the regenerator may be designed for high velocity operation involving linear superficial gas velocities of from about 15 2.5 to 4 feet per second. However, the superficial velocity of the upflowing gases may vary from about 1-5 and higher. Catalyst losses are minimized and substantially prevented in the reactor by the use of multiple stages of cyclone 20 separators. These cyclone separators are usually from 2 to 3 and more stages.

Distributing grids may be employed in the reaction and regeneration zones. Operating temperatures and pressures may vary appreciably 25 depending upon the feed stocks being processed and upon the products desired. Operating temperatures are, for example, in the range from about 800° to 1000° F., preferably about 850-950° F., in the reaction zone. Elevated pressures 30 may be employed, but in general pressures below 100 lbs. per sq. in. gauge are utilized. Pressures generally in the range from 1 to 30 lbs. per sq. in. gauge are preferred. A catalyst holdup corresponding to a space velocity of 1 to 20 weights 35 per hour of feed per weight of catalyst is utilized. A preferred ratio is 2 to 4. Catalyst to oil ratios of about 3 to 10, preferably about 6 to 8 by weight are used.

40 The catalytic materials used in the fluidized catalyst cracking operation, in accordance with the present invention, are conventional cracking catalysts. These catalysts are oxides of metals of groups II, III, IV and V of the periodic table. A preferred catalyst comprises silica-alumina 45 wherein the weight per cent of the alumina is in the range from about 5 to 20%. Another preferred catalyst comprises silica-magnesium where the weight per cent of the magnesia is about 5% to 20%. These catalysts may also contain a third 50 constituent, as for example, ThO₂, WO₃, MoO₃, BeO, Bi₂O₃, CdO, UO₃, B₂O₃, SnO₂, Fe₂O₃, V₂O₅, MnO, Cr₂O₃, CaO, Tl₂O₃, MgO and Ce₂O₃ present in the concentration from 0.05% to 0.5%. The size of the catalyst particles is usually below 55 about 200 microns. Usually at least 50% of the catalyst has a micron size in the range from about 20-80. Under these conditions with the superficial velocities as given, a fluidized bed is maintained wherein the lower section of the 60 reactor, a dense catalyst phase exists while in the upper area of the reactor a dispersed phase exists.

The above described operation as pointed out, 65 has not been entirely satisfactory for cracking heavy oils such as a reduced crude due to excessive formation of carbon on the catalyst. However, by combining the phosphorus and water treating stages with the catalytic cracking stage, an improved operation results when using feed stocks of this character. The process of the present invention may be further understood by the following examples, further illustrating the same.

Example I

75 A non-desalinated South Louisiana crude was

distilled to about 2.4% bottoms and the residuum thus obtained was heated with 85% H_3PO_4 to various temperatures. The residuum had the following inspections:

Feed	2.4% South Louisiana Vacuum Residuum
Gravity, °API	11.9
Conradson Carbon, Wt. Percent	17
Viscosity, SSF at 210° F.	396
Pour, ° F.	105
Carbon, Wt. Percent	85.6
Hydrogen, Wt. Percent	11.3
H/C Atomic Ratio	1.57
Sulfur, Wt. Percent	0.73
Ash, Wt. Percent	0.52

The products were diluted with gas oil to reduce the viscosity and water-washed by injecting steam through a fritted tube. The water washing resulted in the formation of some water-in-oil emulsion which was broken by treatment with an electric field and allowed to settle. The product was analyzed for total ash and for the particularly potent catalyst poisons, iron and vanadium oxides. The following results were calculated on an added gas-oil-free basis:

Run No.	H_3PO_4 Treat	Water-Wash	Pounds/Thousand Barrels		
			Ash	Fe_2O_3	V_2O_5
1.	Feed	No.	1,728	69	3
1.	None (but sample washed)	Yes	320	—	4
2.	2 Hrs., 600° F., 2% H_3PO_4	Yes	50	5	3
3.	1 Hr., 720° F., 2% H_3PO_4	Yes	51	—	—
4.	2 Hrs., 600° F., 1% H_3PO_4	Yes	78	1	1

Example II

A 10% residuum from desalinated South Louisiana crude was heated with 2.0% of 85% H_3PO_4 for 2-6 hours at 600-675° F. in the same manner as in Example I. After the treatment with H_3PO_4 , the material was water washed, the water was decanted off and the product analyzed for ash. The following results were obtained:

Run No.	H_3PO_4 Treat	Water-Wash	Pounds/Thous. Barrels in Product		
			Ash	Fe_2O_3	V_2O_5
0.	Feed	No.	102	—	—
1.	None (but sample washed)	Yes	28	3	6
2.	2 Hrs., 600° F., 2% H_3PO_4	Yes	18	0.4	0.6
3.	2 Hrs., 675° F., 2% H_3PO_4	Yes	38	1	1
4.	6 Hrs., 600° F., 2% H_3PO_4	Yes	29	0.4	1

Example III

Residua from (I) West Texas and (II) a mixture of Louisiana and Texas crudes were treated with 2% of 85% H_3PO_4 at 600° F. for two hours and water washed in accordance with Example I with the following results:

The West Texas residuum had the following inspections:

Feed	16% West Texas Atmos. Residuum
Gravity, °API	11.0
Conradson Carbon, Wt. Percent	14
Viscosity, SSF at 210° F.	186
Pour, ° F.	90
Carbon, Wt. Percent	85.6
Hydrogen, Wt. Percent	11.0
H/C Atomic Ratio	1.54
Sulfur, Wt. Percent	2.75
Ash, Wt. Percent	0.11
ASTM Distillation:	
Initial, ° F.	714
5% at ° F.	843
10% at ° F.	918

The results of the operations were as follows:

Run No.	Feed	H_3PO_4 Treatment	Water-Wash	P. T. B. in Product Residuum		
				Ash	Fe_2O_3	V_2O_5
1.	16% West Texas Residuum.	No.	No.	372	—	—
2.	do	No.	Yes	68	0.3	29
3.	do	Yes	Yes	57	—	17
4.	Mixed La. and Texas Residua.	No.	No.	1,050	—	—
5.	do	No.	Yes	232	7	39
6.	do	Yes	Yes	132	0.3	1

The above examples clearly show that oil soluble ash constituents are removed from residual stocks by heating the residua with 1 to 2% H_3PO_4 at temperatures of 600-700° F. followed by water washing. The iron and vanadium constituents of the ash are significantly reduced.

What is claimed is:

1. Improved process for the production of hydrocarbon constituents boiling in the motor fuel boiling range from a feed oil boiling above about 600° F. which comprises contacting said feed oil in an initial stage with from about 0.5 to 10% by weight of an acid of phosphorus at an elevated temperature, removing the oil and contacting the same in a secondary stage with a washing solvent, separating the residue from the treated oil and then contacting said oil with a fluidized cracking catalyst at elevated temperatures and pressures adapted to crack the oil and produce hydrocarbon constituents boiling in the motor fuel boiling range.
2. Process as defined by claim 1 wherein the feed oil is an oil which boils above about 860° F.
3. Process as defined by claim 1 wherein the temperature employed in the initial zone wherein the oil is contacted with an acid of phosphorus is in the range from about 600° to 700° F.
4. Process for the production of hydrocarbon constituents boiling in the motor fuel boiling range which comprises treating a feed oil having a gravity in the range from about 6° API to 15° API and boiling above about 600° F., with from about 0.5 to 10% by weight of an acid of phosphorus having a concentration in the range from about 80% to 90% at a temperature in the range from about 600° F. to 700° F., removing the treated feed oil and washing the same with water in a temperature in the range from 600° F. to 700° F., separating the water and thereafter subjecting the said feed oil to a temperature in the range from about 800° F. to 1050° F., and at a pressure below about 100 lbs. per sq. in. gauge, to the effect of a cracking catalyst, removing a cracked product and separating a fraction boiling in the motor fuel boiling range.
5. Process as defined by claim 4 wherein the amount of acid of phosphorus utilized is in the range from about 1% to 3% by weight.
